FRANK B. COOK COMPANY, OF CHICAGO, ILLINOIS, A CORPORATION OF ILLINOIS.

TELEPHONE SYSTEM.

1,105,348.

Specification of Letters Patent.

Patented July 28, 1914.

Application filed June 24, 1912. Serial No. 705,412.

To all whom it may concern:

Be it known that I, CHARLES A. BALS, a citizen of the United States, residing at Chicago, in the county of Cook and State of Illinois, have invented a certain new and useful Improvement in Telephone Systems, of which the following is a full, clear, concise, and exact description, reference being had to the accompanying drawings, forming a part of this specification.

My invention relates to telephone systems and in its preferred embodiment includes switching mechanism forming the subject matter of my co-pending application Serial 15 No. 705,413, filed June 24, 1912 but the present invention is not to be limited to the employment of such switching mechanism.

The system of my present invention is a so-called intercommunicating system in which 20 the telephone stations are provided with means to enable intercommunication therebetween without the aid of an exchange though in some systems means are provided to also enable telephonic communication between any of the stations of the system and telephone lines which extend to an exchange.

Heretofore mechanism was employed which, among other functions, had the function 30 of locking the telephone station sets in circuit relation with the lines, which have become telephonically related to such sets, while the telephone receivers are free of their switch hooks. It is frequently desirable to permit the intercommunicating station party to temporarily hold a line with which his telephonic apparatus has become 35 telephonically connected after such telephonic connection has ceased in order, for example, that conversation may be held 40 which will not be telephonically transmitted over the line that is thus to be temporarily held in telephonic disconnection.

My invention has for its object the provision 45 of switching mechanism whereby such electro-magnetically controlled mechanism at an intercommunicating telephone station may be operated to sever the telephone connection of a line with such station during 50 the time that the telephone receiver at such station is free of its hook, the switching mechanism also including parts whereby the telephonically disconnected line may have its line equipment maintained *in status quo* so that the party at such intercommuni-

cating station may resume his telephonic connection with the line that was temporarily telephonically disconnected. In the preferred embodiment of the invention a single switch structure is adapted to hold such 60 line and to effect the operation of the electro-magnetic mechanism to effect the desired telephonic disconnection.

I will explain my invention more fully by reference to the accompanying drawing 65 showing the preferred form of the invention as it is embodied in connection with one type of intercommunicating telephone systems whose stations are adapted for connection with an exchange through the inter- 70 mediation of a trunk line. I will not fully describe the apparatus illustrated at each of the stations A, B, C as there are so many features which are illustrated which do not form a part of my present invention and to 75 which my present invention is not to be limited.

The apparatus at each station includes a telephone receiver 1, a telephone transmitter 2, a telephone switch hook 3 for including 80 the telephone transmitter and receiver in circuit with and excluding from the circuit of telephonic conductors 4 and 5 which are extended into the multiple connections with the contact springs 6 and 7 of keys 8 (individual to each of the lines extending to the stations where such keys are located) when the key 9 is in the position indicated at station B. Each of the keys 8 at each of the stations is provided with contacts 10 and 11 85 which are normally separated from the contacts 6 and 7 but which are, respectively, engaged thereby when the key 8 at a station which is calling any of the other stations of the intercommunicating system or any station which is called from an exchange is depressed, it being assumed that a line called from an exchange is free for selection or that the called intercommunicating 90 line is free for appropriation by the calling 100 intercommunicating party. When the telephonic equipment at an intercommunicating station is thus brought into telephonic connection with any telephone line extending to such station, such telephone equipment is held in this relationship (while the receiver is off its hook) by means of the dog 12 that 105 engages a lug 13 provided upon the switch 9, such engagement being illustrated at station B. Each dog 12 is pivotally mounted 110

upon a swinging plate 14 which is engageable by a pin 15 provided upon the lower end of each bar 16. The bar 16 at each station is provided with pins 17 that are worked upon by the keys 8 when the keys are depressed. The equipment at station A is in condition to permit the keys 8 thereat to be depressed. When a key thus free to be depressed is so depressed, the free end of the plate 14 is engaged under the lug carried by the upper end of the armature 18 as illustrated at station B whereby the element 19 is removed from the path of travel of the plunger element of the key 9 whereby the lug 13 is free to ride under the dog 12 so that the nose of said dog will engage the lug, as illustrated at station B, to hold the key in its depressed position as is necessary in the establishment of telephonic connection between the associate telephone set 1, 2 and the line to which the actuated key 8 is individual. As the invention is embodied, the telephone equipment 1, 2 thus locked in telephonic association is mechanically locked 25 without the coincident aid of any electromagnet though I do not limit myself to this characteristic. The telephonic connection thus mechanically held is adapted to be broken by the associate magnet 20 which, 30 when energized, swings the armature 18 to break the engagement between the armature and the associate plate 14 whereupon the dog 12 carried by such plate is raised out of engagement with the lug 13 to permit the 35 plunger element of the key 9 automatically to be thrust back so as to break the previously held telephonic connection. To this end the magnet 20 at one or more of the stations (the equipment now to be described 40 being shown at station A only) is provided with a controlling circuit and suitably associated switching mechanism, such circuit being traceable from the lower pole of the battery 21, the winding of magnet 20, the 45 now engaged contacts 22, 23, the contacts 24 and 25 of the holding key mechanism to the upper terminal of the battery 21. The contacts 24 and 25 are normally disconnected in order that the magnet 20 may remain inert 50 during the time the associate telephone outfit 1, 2 is mechanically locked in circuit.

The contacts 24 and 25 form part of unitary switching mechanism that includes the contacts 26 and 27 that are normally separated to keep open the bridge conductor across the sides of the trunk line 29, 30 and which bridge conductor includes a magnet 28. When the magnet 28 is energized upon the closure of the contacts 26, 27 (which 60 closure is effected when the closure of contacts 24 and 25 is effected with the results stated) contacts 31 and 32 are closed for the purpose of maintaining the continuity of the bridge conductor through the winding 65 28 when the holding key lever 33 is released.

The armature of the magnet 28 may be provided with a visual signal attachment 34 to indicate to the operator whether or not the trunk line is held. The trunk line extends to an exchange (which need not be illustrated) the bridge which is established through the magnet 28 replacing the bridge that was previously established across the trunk line through the telephonically released equipment 1, 2. The magnet 28 is in 70 high resistance so that when the telephone equipment 1, 2 is again bridged across the trunk line the magnet will be shunted as a consequence of the comparatively low resistance of the bridge conductor including 80 the elements 1 and 2.

The purpose of the holding magnet 28 is to maintain the equipment that is associated with the trunk line at the exchange to which the trunk line extends *in status quo* whether 85 such trunk line extends to an exchange where it is either manually or automatically extended or not.

A calling party at, say station B, in calling first removes his telephone receiver 1 90 from the line associated with the electro-8 individual to the called station, say station A. If station A is idle circuit for the magnet 20 at the calling station is open at the telephone bridge of the called station so that 95 the armature of the magnet 20 of the calling station remains unattracted whereby the switch spring 14, consequent upon the depression of the bar 16 will remain depressed owing to the engagement of this switch 100 spring 14 at 18. The key 9 may now be depressed, owing to the illustrated relationship of its parts 13, 19 to establish circuit for the bell at the called station A, if the called station is idle, which circuit may be traced from the upper pole of the battery 21¹, the bell 21² at the called station, the switch parts at 23 of the key 9 at the called station, the lower contacts of the switch hook 3 at the called station, the contacts 7, 11 of the depressed key 8 at the calling station, the contacts 22¹ of the fully depressed key 9 at the calling station, thence back to the lower pole of the battery 21¹. After the called subscriber at 105 station A responds telephonic circuit is established which is traceable from the transmitter 2 at the calling station, the closed contacts 22² at this station, the contacts 6 and 10 of the depressed key 8, the contact 22³ and its complemental contact at the called station, the conductor 5, the transmitter 2 at the called station, the receiver 1 at this station, the upper contacts of the switch hook 3 at this station, the associate conductor 4, the contacts 22⁴ of the key 9 at the called station, the contacts 7, 11 of the key 8 at the calling station, the lower contact 22¹ and the two contacts beneath it at the calling station, the conductor 4 at this station, the upper 110 pair of switch hook contacts at this station, 13

the receiver thereat, thence to the transmitter 2 at the calling station.

If the calling station, say station B, should desire connection with the exchange the key 8 individual to the trunk line leading to the exchange is depressed and if the line is free for use the magnet 20 at the calling station is not energized owing to the absence of battery from the contacts 11. As is well known in telephone practice, the telephone bridge at the calling station will operate the line signal at the exchange which is connected with the trunk line. It is obvious that the telephonic connection will now include the contacts 6, 7, 10 and the contact below the contact 7 of the depressed key 8 individual to the trunk line, the circuit at the calling station end of the telephone circuit being apparent from the previous description. If the trunk line is busy it is owing to the depression of the key 8 at some other station, in which event the magnet 20 at the calling station receives current by way of the lower contacts at 11 and the contacts immediately above the same of the key 8 of the calling station and the key 8 at the station which has taken the trunk line for use. When the calling party restores his telephone upon its switch hook circuit for his magnet 20 is closed through the battery 21, this circuit being traceable from the lower pole of this battery, the winding of the magnet 20 at the calling station, contacts 22 and 23 at the calling station, the lower contacts of the switch hook 3 at the calling station, the contacts 22⁵ at the calling station, thence back to the upper pole of the battery 21.

It will thus be seen that I have provided a holding switch mechanism which, by one operation, will enable the telephone equipment connected with the trunk line automatically to be disconnected from such line while the line equipment of the trunk line is held *in status quo* to guard against its disconnection at the exchange to which it extends, a result which is accomplished without the restoration of the receiver 1 upon its switch hook, and while the holding switch happens to be associated with the trunk line, I do not wish to be limited to this characteristic.

Having thus described my invention, I claim as new and desire to secure by Letters Patent the following:—

1. An intercommunicating telephone system including telephone lines extending between stations of the system, such stations including telephone receivers and their supporting switch hooks that take part in governing the telephonic association of the stations; electro-magnetically controlled mechanism associated with one of the stations for maintaining the telephonic circuit thereat; switching mechanism supplied in addition to the switch hook for altering the circuit

circuit of the electro-magnetically controlled mechanism to effect the telephonic disconnection of the station having such switch hook; and a holding switch for preserving the circuit of the telephone line that has become telephonically disconnected from the line associated with the electro-magnetically controlled mechanism. 70

2. A telephone system including two telephone lines extending to telephone stations, one of said stations having telephonic equipment that includes a telephone receiver and its supporting switch hook that takes part in governing the telephonic association of its station with its line; electro-magnetically controlled mechanism associated with the line whose station is provided with the switch hook for maintaining telephonic circuit thereat; switching mechanism supplied in addition to such switch hook for altering the circuit of the electro-magnetically controlled mechanism to effect the telephonic disconnection of the station having such switch hook; and a holding switch for preserving the circuit of the telephone line 80 that has become telephonically disconnected from the line associated with the electro-magnetically controlled mechanism. 85

3. An intercommunicating telephone system including telephone lines extending between stations of the system, such stations including telephone receivers and their supporting switch hooks that take part in governing the telephonic association of the stations; electro-magnetically controlled mechanism associated with one of the stations for maintaining the telephonic circuit thereat; switching mechanism supplied in addition to the switch hook for altering the circuit of the electro-magnetically controlled mechanism to effect the telephonic disconnection of the station having such switch hook; a holding switch for preserving the circuit of the telephone line that has become telephonically disconnected from the line associated with the electro-magnetically controlled mechanism; and an electro-magnet made effective by the holding switch to maintain the circuit established by the holding switch, there being circuit connections 100 105 where by the telephonic equipment whose line is associated with said electro-magnetically controlled mechanism, when again telephonically connected with the line provided with the holding switch, will effect the operation of said electro-magnet to restore the circuit connections it controls. 110 115

4. A telephone system including two telephone lines extending to telephone stations, one of said stations having telephonic equipment that includes a telephone receiver and its supporting switch hook that takes part in governing the telephonic association of its station with its line; electro-magnetically controlled mechanism associated with the 120 125 130

line whose station is provided with the switch hook for maintaining telephonic circuit thereat; switching mechanism supplied in addition to such switch hook for altering 5 the circuit of the electro-magnetically controlled mechanism to effect the telephonic disconnection of the station having such switch hook; a holding switch for preserving the circuit of the telephone line that has become telephonically disconnected from the line associated with the electro-magnetically controlled mechanism; and an electro-magnet made effective by the holding switch to maintain the circuit established by the holding switch, there being circuit connections 10 15

whereby the telephonic equipment whose line is associated with said electro-magnetically controlled mechanism, when again telephonically connected with the line provided with the holding switch, will effect the operation of said electro-magnet to restore the circuit connections it controls. 2

In witness whereof, I hereunto subscribe my name this twentieth day of May A. D., 1912.

CHARLES A. BALS.
